DIVINING ROD

Roy Rickard, 314 Wasaon St., Toledo, Ohio

Filed Aug. 23, 1961, Ser. No. 66,469

Term of patent 14 years

(Cl. D52—1)

FIG. 1 is a perspective view;
FIG. 2 is a front elevation view;
FIG. 3 is a side view;
FIG. 4 is a top plan view; and
FIG. 5 is a bottom plan view of a divining rod showing my new design.

I claim:

The ornamental design for a divining rod as shown.
